HENRY W. SCHOFF, DANIEL W. YOUNG, JR., AND AUGUST C. DOBRICK, OF CHICAGO,
ILLINOIS, ASSIGNORS TO THE IMPERIAL BRASS MANUFACTURING COMPANY, OF
CHICAGO, ILLINOIS, A CORPORATION OF ILLINOIS.

SELF-HEATING FLAT-IRON.

1,146,025.

Specification of Letters Patent. Patented July 13, 1915.

Application filed August 3, 1914. Serial No. 854,715.

To all whom it may concern:

Be it known that we, HENRY W. SCHOFF, DANIEL W. YOUNG, Jr., and AUGUST C. DOBRICK, citizens of the United States, and residents of Chicago, in the county of Cook and State of Illinois, have invented certain new and useful Improvements in Self-Heating Flat-Irons, of which the following is a full, clear, and exact specification.

10 Our invention is concerned with self-heating flat-irons, and is designed to produce a device of the class described that shall be provided with an efficient vaporizer and burner for hydrocarbons so that it can be used indefinitely, even with the most difficult of such oils, such, for instance, as kerosene, to burn which it is more especially designed.

To this end, our invention consists in certain novel features and combinations, all of which will be fully described in the following specification, and more particularly pointed out in the claims.

To illustrate our invention, we annex hereto three sheets of drawings, in which the same reference characters are used to designate identical parts in all the figures, of which,—

Figure 1 is a side elevation of the complete iron; Fig. 2 is a vertical section on the line A—A of Fig. 1; Fig. 3 is a vertical section on the line B—B of Fig. 2; Fig. 4 is an end elevation, partly in section, on the line C—C of Fig. 3; Fig. 5 is a top plan view, with the tank and the cover for the iron removed; Fig. 6 is a horizontal section on the line D—D of Fig. 1; Fig. 7 is an inverted plan view of the burner-casting, with the screen and spreader-plate omitted; Fig. 8 is an inverted plan view of the spreader-plate detached; Fig. 9 is a similar view of the burner-screen; Fig. 10 is a detail in section, on an enlarged scale, on the line E—E of Fig. 5; Fig. 11 is a detail of a portion of the mechanism seen in Fig. 6, on an enlarged scale; Figs. 12 and 13 are details, in cross section, on the lines F—F and G—G, respectively, of Fig. 11; and Figs. 14 and 15 are details in section, on an enlarged scale, on the lines H—H and I—I, respectively, of Fig. 6.

In carrying out our invention, the iron proper, 20, may be of any desired shape or design, and is of course hollow, and has the

bottom 21, upon the upper surface of which the flame is directed, so that the heat will be passed on through the bottom and to the materials being ironed. The cover-plate 22 is preferably made of comparatively thin metal, and has a lug 23 extending from the lower side of one end thereof and adapted to cooperate with the aperture 24 in the nose of the iron. A swinging catch 25 is preferably pivoted on the edge of the iron at 26, so that when the cover is in place, the catch can be swung over the rear end thereof to hold the cover and the attached handle 27 securely in place on the iron. The handle 27 is of course supported by a suitable yoke, such as the sheet-metal one 28 shown as having the handle secured in the upper end thereof and as held in place on the cover by screws 29 passing through the yoke, the lugs or spacing collars 30 on the top of the cover 22, and through said cover, the screws 29 being preferably provided with nuts 31 beneath the cover. To keep some of the heat from the cover, and thus furnish some protection for the hand of the user, we secure on the under side of the cover, at a little distance therefrom, a plate 32, which covers the entire surface beneath which the flame is burning, so as to form an air space between the plate 32 and the cover 22, thus insulating the handle to some extent. As a convenient method of securing this plate 32 in place, the ends of the screws 29 may be extended therethrough and riveted, so that the plate is held against the nuts 31.

The fuel to be vaporized is placed in a small, preferably cylindrical, tank 33, which has a suitable filling aperture in its upper end, closed by a screw-cap 34, which may be of any desired design, and which is provided with any desired form of air check-valve, so that air under pressure may be forced into the tank through an air pump, or other source of compressed air, which is attached to the nozzle 35. We preferably provide an additional valve 36 to cooperate with the check-valve and prevent the possibility of any leakage. The upper end of the stem of the valve 36 is preferably squared and provided with a flange 37, so that a detachable wooden handle 38, having a suitably squared aperture in its center, may be applied thereto when it is desired to manipulate the valve. The valve-stem 39 for the

needle-valve is similarly provided with a squared end 40, so that the same removable wooden or other heat-insulating handle 38 may be applied thereto when necessary, and 5 removed when its use is not desired. The lower end of the tank 33 is provided with a suitable, centrally located screw-threaded aperture, by which the tank is securely screwed onto the threaded upper end 10 of the supporting and oil-supplying tube 41, which preferably has a loop 42 therein extending through a complete circle, so as to give additional length to said tube. The upper end of the tube 41, as best seen in Fig. 15, is closed by a small metallic screen 43 fitted therewith, which serves to catch any solid impurities which might be in the oil. The other end of the tube 41 is secured in the arm 44 of the vaporizer 45, the details of which will be described more at length farther on. To hold the arm securely in place and without the possibility of its turning, we employ the construction best shown in Figs. 11, 12 and 13, where it will be seen that the horizontal end of the tube 41 is hexagonal on its outer surface and fits into a hexagonal portion 45 of the aperture leading through the arm 44 and opening into the aperture through which 20 the needle-valve 39 passes. The horizontal end of the tube 41 has secured thereon, adjacent the hexagonal portion, a packing ring 46, which will be seen to be provided with two tapered surfaces, one of which co-operates with the surface 47 in the interior of the arm 44, while the other co-operates with the flaring inner end of the union nut 48 threaded into the arm 44 and serving, when it is screwed up, to securely fasten the tube 41 into its place in the arm 44. To further strain out the kerosene and secure the deposit of any particles of impurity therein, we place in the horizontal portion of the tube 41 a roll of wire gauze 49, which is preferably rolled around the wire 50, having a hook at its outer end, so that by pulling on the projecting inner end, the gauze may be pulled out of the tube when it is desired to clean the same. 50

The vaporizer casting 45, in addition to the arm 44 just considered, has an arm 51, the outer end of which is threaded so as to have screwed thereon a packing nut 52, which is employed to force the packing 55 53 against the stem of the needle-valve 39, which valve has a threaded portion 54 co-operating with an interiorly threaded portion of the passage extending through the generator or vaporizer 45. Beyond the threaded portion 54 of the needle-valve 39 is a reduced portion 55, which is square or triangular, or some such shape in cross section, so that its comparatively sharp edges 60 65 will scrape against the circular cross-section of the portion of the passage with which it

co-operates, to clear said passage from the deposits of carbon as the valve is manipulated. The passage for supplying the oil through the arm 44 opens into the passage through the vaporizer at a point beyond the 70 threaded portion 54, so that the square portion 55 of the valve permits the oil to pass along the cut-off sides of the valves. The extreme inner end of the valve is provided with the customary needle-point 56, which 75 closes a fine aperture 57 formed in the circular end of the vaporizer-casting, which circular end fits in a correspondingly shaped and sized aperture 58 formed in the rear end of the burner-casting. The vaporizer-casting 45 has a rectangular portion 59, which fits in a correspondingly shaped aperture 60 in the rear end of the iron proper, and a lug 61 is formed on the inner end, through which a screw 62 is passed and 80 threaded into a lug 63 formed on the burner so that the screw 62 serves to rigidly secure the vaporizer to the burner. An aperture 64, somewhat smaller than the aperture 60, is formed in the iron beneath the aperture 60, and is normally substantially closed by a swinging cover 65 pivoted to the plate 59 at 66, so that it can be swung up out of the way, and a torch partially introduced through the aperture 64, so that the flame 90 therefrom will strike the generator and raise it to a vaporizing heat. To increase the surface exposed to the heat of the torch and to the sub-flame to be described, the generator-casting 45 has formed thereon wings 67. 95

The burner-casting is shown detached in Fig. 7, and in position in Figs. 2, 3, 5 and 6, where it will be seen to be of a generally T-shape in its horizontal cross-section, and to have the tubes 68 extending in both directions from the end and fitting in recesses formed in the sides of the iron. It will of course be understood that these tubes 68 are to supply the air for the Bunsen flame, and the aperture 57 for the needle-valve opens 100 into these tubes where they join with the mixing passage or chamber 70, which extends through the length of the burner-casting and terminates in the enlarged portion 71. This enlarged portion 71 is provided 105 with a deflecting concave flange 72 which serves to turn the vapor back toward the needle-valve, the vapor, however, passing out from a semicircular aperture 73 formed in the bottom of the burner, and into a passage, substantially circular in cross section, formed by a longitudinal cavity 75 formed in the under side of the burner-tube and by the concave upper surface 76 of the deflecting plate 77, which is seen detached in Fig. 115 8. The vapor thus directed back into the passage, substantially circular in cross section is thrown to the rear of the burner, where a number of slots 79 are cut in the rounded end thereof so as to form a sub- 120 125 130

flame which is directed against the generator, and more especially the inner end thereof with the wings 67; this sub-flame of course performing the customary function of keeping the generator up to a vaporizing heat so long as the iron is in operation. The deflecting plate 77 has a semicircular aperture 80 cut into its upturned end to form the opening into the passage, substantially circular in cross section, and it has at its four corners the downwardly turned lugs 81, which coöperate with the upper surface of the burner-plate 82 to hold the deflector-plate in position. The burner-plate 82 is a metal screen preferably formed by punching apertures therein with the rough edges downward, and it is shaped to fit in and fill the boat-shaped bottom of the burner-casting, which is formed by a downwardly extending flange 83. This flange 83 has formed on its inner surface eight ribs 84, the central four of which coöperate with the recesses 85 formed in the edges of the deflector-plate to position the latter. The lower ends of these flanges 84 form seats for the screen or burner plate 82, and when the parts are assembled, the lugs 86 formed on the flange 83 below the ribs 84 are turned over to clamp the screen or burner plate 82 in place; and when it is clamped in place, its coöperation with the lugs 81 on the deflector-plate serves to hold the latter in place. This deflector-plate is provided with a plurality of apertures 87, so that when the iron is started, and the generator is hot enough to vaporize, the needle-valve is opened gradually, the first vapor passing out being deflected back through the sub-flame burner-opening 79, and as more vapor is turned on, the excess passes down through the apertures 87 in the deflector-plate and through apertures 88 punched in the burner-plate 82, so that a solid flame is formed on the bottom of said plate. A set screw 89, or some similar lug, serves to support the inner end of the burner-casting in place, and the plate 32 rests on the lugs 90 and 63 formed on the upper surface thereof, so that the parts are all properly held in place.

The operation of the above-described apparatus will of course be readily understood, by those skilled in the art, from the foregoing description of its structure, and we have found by extended experiments that an iron constructed as herein shown and described will operate satisfactorily for a long period of time, and can be readily cleaned and kept in order.

While we have shown and described our invention as embodied in the form which we at present consider best adapted to carry out its purposes, it will be understood that it is capable of modifications, and that we do not desire to be limited in the interpreta-

tion of the following claims except as may be necessitated by the state of the prior art.

What we claim as new, and desire to secure by Letters Patent of the United States, is:

1. In a self-heating flat-iron, the combination with a hollow iron, a cover, and a handle; of a tank, a vaporizer located in the iron adjacent the tank which it supports, a burner including a mixing chamber extending from the vaporizer toward the other end of the iron and directing its main flame downward, and having a sub-flame directed rearwardly therefrom against the vaporizer, and an air-supply tube extending from the mixing chamber to the surface of the iron. 75

2. In a self-heating flat-iron, the combination with a hollow iron, a cover, and a handle; of a tank, a vaporizer located in the iron adjacent the tank which it supports, a burner including a mixing chamber extending from the vaporizer toward the other end of the iron and directing its main flame downward, and having a sub-flame directed rearwardly therefrom against the vaporizer, and a pair of air-supply tubes extending at 90 right angles from the mixing chamber to the sides of the iron. 85

3. In a self-heating flat-iron, a burner-casting comprising an oblong lower portion with downwardly projecting flanges, and a 95 T-shaped upper portion having a mixing-chamber body extending the length of the lower portion and opening thereinto at one end, and air-supply tubes extending at right angles from the other end. 100

4. In a self-heating flat-iron, a burner-casting comprising an oblong lower portion with downwardly projecting flanges, and a T-shaped upper portion having a mixing-chamber body extending the length of the 105 lower portion and opening thereinto at one end, and air-supply tubes extending at right angles from the other end, and having an aperture intermediate the supply tubes and adapted to receive the valve end of a vaporizer. 110

5. In a self-heating flat-iron, a burner-casting comprising an oblong lower portion with downwardly projecting flanges, and a 115 T-shaped upper portion having a mixing-chamber body extending the length of the lower portion and opening thereinto at one end, a deflecting flange beneath the opening, and air-supply tubes extending at right angles from the other end. 120

6. In a self-heating flat-iron, a burner-casting comprising an oblong lower portion with downwardly projecting flanges and apertures forming a sub-flame burner at one end of said lower portion, and a T-shaped 125 upper portion having a mixing-chamber body extending the length of the lower portion and opening thereinto at one end, a

deflecting flange beneath the opening, air-supply tubes extending at right angles from the other end of the mixing chamber, and an aperture intermediate the supply tubes adapted to receive the valve end of a vaporizer supported above the sub-flame burner.

7. In a device of the class described, the combination with a burner having an oblong lower portion, of a burner-screen closing the bottom of said lower portion, a sub-flame burner formed at one end of said lower portion, a mixing chamber extending along the upper portion and opening into the lower portion at one end thereof, and a vaporizer secured to the other end of the burner and having its needle-valve opening into the mixing chamber and located so as to be struck by the sub-flame.

8. In a device of the class described, the
20 combination of a burner having an oblong
lower portion, a burner-screen closing the
bottom of said lower portion, a sub-flame
burner formed at one end of said lower portion,
25 a mixing chamber extending along the
upper portion and opening into the lower
portion at one end thereof, and a vaporizer
provided with wings for increasing the heat-
ing surface secured to the other end of the
burner and having its needle-valve opening
30 into the mixing chamber and located so as
to be struck by the sub-flame.

9. In a device of the class described, the combination of a burner having an oblong lower portion, a burner-screen closing the bottom of said lower portion, a sub-flame burner formed at one end of said lower portion, a mixing chamber extending along the upper portion and opening into the lower portion at one end thereof, and a vaporizer secured to the other end of the burner and having its needle-valve opening into the mixing chamber and located so as to be struck by the sub-flame, said vaporizer having an end fitting into an aperture formed in the adjacent end of the mixing chamber.

10. In a device of the class described, the combination of a burner having an oblong lower portion, a burner-screen closing the bottom of said lower portion, a sub-flame burner formed at one end of said lower portion, a mixing chamber extending along the upper portion and opening into the lower portion at one end thereof, a deflecting flange cooperating with said opening to throw the vapor back to the sub-flame burner, and a vaporizer secured to the other end of the burner and having its needle-valve opening into the mixing chamber and located so as to be struck by the sub-flame.

60 11. In a device of the class described, the combination of a burner having an oblong lower portion, a burner-screen closing the bottom of said lower portion, a sub-flame burner formed at one end of said lower portion, a mixing chamber extending along

65

the upper portion and opening into the lower portion at one end thereof, a deflecting flange coöoperating with said opening to throw the vapor back to the sub-flame burner, a passage in said lower portion leading from the deflecting flange to the sub-flame burner, and a vaporizer secured to the other end of the burner and having its needle valve opening into the mixing chamber and located so as to be struck by the sub-flame. 75

12. In a device of the class described, the combination of a burner having an oblong lower portion, a burner-screen closing the bottom of said lower portion, a sub-flame burner formed at one end of said lower portion, a mixing chamber extending along the upper portion and opening into the lower portion at one end thereof, a deflecting flange coöperating with said opening to throw the vapor back to the sub-flame burner, a passage in said lower portion leading from the deflecting flange to the sub-flame burner formed by the top of the lower portion of the burner and by a deflecting plate secured in said lower portion, and a vaporizer secured to the other end of the burner and having its needle valve opening into the mixing chamber and located so as to be struck by the sub-flame.

13. In a device of the class described, the combination of a burner having an oblong lower portion, a burner-screen closing the bottom of said lower portion, a sub-flame burner formed at one end of said lower portion, a mixing chamber extending along the upper portion and opening into the lower portion at one end thereof, a deflecting flange 100 coöperating with said opening to throw the vapor back to the sub-flame burner, a passage in said lower portion leading from the deflecting flange to the sub-flame burner formed by the top of the lower portion of the burner and by a deflecting plate secured in said lower portion, and having a concave 105 central portion perforated at suitable intervals to supply vapor to the main burner, and a vaporizer secured to the other end of the burner and having its needle valve opening into the mixing chamber and located so as 110 to be struck by the sub-flame. 115

14. In a device of the class described, the combination of a burner having an oblong lower portion, a burner-screen closing the bottom of said lower portion, a sub-flame 120 burner formed at one end of said lower portion, a mixing chamber extending along the upper portion and opening into the lower portion at one end thereof, a deflecting flange co-operating with said opening to throw the 125 vapor back to the sub-flame burner, a passage in said lower portion leading from the deflecting flange to the sub-flame burner, formed by the top of the lower portion of the burner and by a deflecting plate secured 130

in said lower portion, and having a concave central portion perforated at suitable intervals to supply vapor to the main burner, and having a portion of the concave central portion cut away at the end opposite the sub-flame burner, and a vaporizer secured to the other end of the burner and having its needle valve opening into the mixing chamber and located so as to be struck by the 10 sub-flame.

In witness whereof, we have hereunto set our hands and affixed our seals, this 22nd day of July, A. D. 1914.
